ELECTRON-BEAM FURNACE WITH MAGNETIC
GUIDANCE AND FLUX CONCENTRATOR
Charles W. Hanks, Orinda, Calif., assignor to Stauffer
Chemical Company, New York, N.Y., a corporation of
Delaware

Filed May 27, 1960, Ser. No. 32,328
6 Claims. (Cl. 22—57.2)

This invention relates to electron-beam furnaces for heating materials by electron bombardment in a high vacuum, and particularly for melting materials and casting ingots therefrom, with resulting purification, degasification to an exceptionally high degree, and other benefits.

Briefly stated, electron-beam melting-and-casting furnaces include, within a continuously evacuated tank, a container for the molten material, which most commonly has the form of an annular, water-cooled casting mold open at its top and bottom ends. Solidified material may be progressively withdrawn through the bottom end of the mold to bombard the material therein and maintain a molten pool of material atop the solidifying ingot. Preferably, melt stock is progressively fed into the beam above the open top end of the mold so that the melt stock is continually melted off as it advances into the electron beam. The so-melted material falls into the open top of the mold for continually replenishing the molten material in the pool.

The copending applications of Hugh R. Smith, Jr. Serial No. 32,215, filed May 27, 1960, entitled "Electron-Beam Furnace With Magnetically Guided Beam," and Charles W. Hanks, Serial No. 32,217, filed May 27, 1960, entitled "Electron-Beam Furnace With Double-Coil Magnetic Beam Guidance," and Howard W. Howe, Serial No. 32,216, filed May 27, 1960, entitled "Electron-Beam Furnace With Opposed-Field Magnetic Beam Guidance," all assigned to the same assignee as the present application, disclose and claim improved electron-beam furnaces comprising one or more electromagnet windings that provide a converging magnetic field for guiding electrons into the open top end of the mold.

The present invention is a further improvement providing, among other advantages, a stronger magnetic field in the immediate vicinity of the electron gun, so that the magnetic guidance is more effective upon the initial portions of the electron trajectories. Thus, any tendency for the electrons to move nonparallel to the magnetic flux lines is more forcefully arrested near the electron gun, which assures a better focus of the beam and less spiraling of the electron paths within the magnetic field in the vicinity of the casting mold. Another object and advantage of this invention is that the shape of the magnetic field can be altered somewhat to facilitate variations in the size, shape, and placement of the electron gun, the placement of the melt stock, and the like. Still another object and advantage is the reduction in size of the electromagnet windings relative to the magnetic field strength desired, and the reduction of electric power needed to energize the windings.

In accordance with the present invention, a flux concentrator of ferromagnetic material is arranged adjacent to the electron gun for increasing the magnetic field strength in the vicinity of the gun. A preferred form is a horizontal ring of ferromagnetic material disposed just above an annular electron gun, in vertical, coaxial alignment therewith and with the casting mold, connected through a ferromagnetic yoke to another ring of ferromagnetic material coaxially surrounding the casting mold below the electromagnet windings.

The foregoing and other aspects of the invention will

2

be understood better from the following illustrative description and the accompanying drawings.

FIG. 1 of the drawings is a highly schematic, vertical section of an improved electron-beam furnace.

5 FIG. 2 is a fragmentary schematic, vertical section of the same furnace, drawn to a somewhat larger scale, showing typical magnetic flux lines and electron trajectories.

10 FIG. 3 is a fragmentary schematic, vertical section of another improved electron-beam furnace.

Referring to FIGS. 1 and 2, an annular copper mold 1, with its axis vertical, has open upper and lower ends and is provided with a water jacket 2 through which water or other coolant is continually circulated by conventional 15 means (not shown), whereby the mold is cooled to solidify molten material therein. Other parts of the furnace may also be water-cooled, as desired, such being accomplished by obvious means requiring no description. The solidified material may be progressively withdrawn 20 through the open bottom end of mold 1 to form a cast ingot 3 of progressively increasing length, which may be cut off from time to time as desired. Progressive withdrawal of the ingot is accomplished, for example, by means of rollers 4 driven by an electric motor 5.

25 A first annular electromagnet winding 6 extends coaxially around mold 1, as shown, and has a vertical axis concentric with the open top of the mold. Preferably, this winding is protected by an inner sheath 7 of insulation and an outer sheath 8 of metal. Wires 9 and 10 connect

30 winding 6 to a D.C. power supply 11 in series with a rheostat 12, whereby the winding 6 is supplied with energizing direct current of adjustable magnitude. A second electromagnet winding 13 is vertically spaced above the

35 first winding, in vertical coaxial alignment with the first winding 6 and the annular mold 1. Preferably, winding 13 is protected by an inner sheath 14 of insulation and an outer sheath 15 of metal. Wires 16 and 17 connect winding 13 to D.C. power supply 11 in series with a rheostat 18, whereby winding 13 is supplied with energizing direct current of adjustable magnitude. The two windings 40 6 and 13 are energized in additive magnetic flux relation, and the energizing currents supplied to the two windings are individually adjustable by means of rheostats 12 and 18. The so-energized windings produce a magnetic field

45 having magnetic flux lines that extend and converge downwardly through the center opening of winding 13 into the open top end of mold 1, as represented by the broken lines 19, FIG. 2.

An annular electron gun, vertically spaced above winding 13 in vertical coaxial alignment therewith and with mold 1, directs a beam of electrons along the magnetic flux lines 19 that converge into the open top end of the casting mold. In its preferred form, the electron gun comprises an annular thermionic cathode 20, most commonly made from a horizontal loop of tungsten wire, connected through leads 21 and 22 and a transformer 23 to an alternating-current supply 24, which provides alternating current through wire 20 for heating the same to thermionic-emission temperature. An accelerating elec-

60 trode 25 is closely spaced below cathode 20 and a focusing electrode 26 is closely spaced above cathode 20, as shown. Preferably, all parts of the gun are made of essentially nonmagnetic materials.

65 Electrical connections are provided for maintaining accelerating electrode 25 at substantially the same electric potential as mold 1, preferably ground potential. This is indicated schematically in the drawing by ground connection symbols 27 and 28. Cathode 20 and focusing electrode 26 are maintained at substantial negative potentials, 70 commonly 5,000 to 15,000 volts, relative to the accelerating electrode. This is accomplished, for example, by

means of connection 29 between electrode 26 and lead 22 and connection 30 between lead 22 and the negative terminal of a high-voltage D.C. supply 31.

The overall design of the electron gun may be similar to that described in the copending patent application of Charles W. Hanks, Serial No. 818,306, filed June 5, 1959, and assigned to the same assignee as the present application. In the present furnace employing a magnetic field to guide the electron beam, the cathode, accelerating electrode, and focusing electrode are shaped and aligned to direct electrons downwardly and inwardly parallel to the converging magnetic lines of force 19, forming a hollow, conelike electron beam, and thereafter the magnetic field plays a significant part in focusing and guiding the electron beam into the open top end of mold 1.

A horizontal feed trough 32 extends inwardly above mold 1 between the vertically spaced windings 6 and 13. Discharge end 32' is adjacent to the open top end of the mold. This feed trough (and thereby its contents) is electrically grounded as indicated by the conventional symbol at 33. Melt stock 34 in any convenient form, e.g., rods, bars, blocks of compacted powder, etc., is fed through trough 32 into one side of the electron beam entering mold 1. Feed mechanism is symbolized by rollers 35 driven by an electric motor 36. As the melt stock emerges from the discharge end of the feed trough, it is bombarded and melted away by the electron beam. The so-melted material falls into the open end of mold 1 for continually replenishing a pool 3' of molten material which rests on top of cast ingot 3 and is supported within a skull or depression that forms automatically within the solidified material.

The general arrangement and operation of the casting mold, annular electron gun, and two electromagnet windings is generally similar to that described in copending patent application Serial No. 32,217 referred to above. The present invention adds a flux concentrator, which preferably comprises two horizontal rings 37 and 38 of ferromagnetic material connected together through a ferromagnetic yoke 39. Ring 37 extends coaxially around the casting mold 1 below electromagnet winding 6, and ring 38 is disposed immediately above the annular electron gun and in vertical coaxial alignment therewith. Yoke 39 passes outside of annular windings 6 and 13. Parts 26 and 38 are spaced apart sufficiently for electrical insulation purposes.

The flux concentrator, and ring 38 in particular, is shaped and aligned to lower the reluctance of magnetic flux paths passing through the electron gun relative to other flux paths, thereby increasing the magnetic field strength in the vicinity of the electron gun. This significantly increases the effectiveness of the magnetic field guidance upon the initial portions of the electron paths near the gun, and imposes a more forceful restraint upon any substantial departure of the electron paths from parallelism with the magnetic flux lines. The additional magnetic restraint and guidance upon the initial portions of the electron paths provides a substantial improvement in beam focus in the vicinity of the casting mold and, in particular, reduces spiralling of the electron paths within the magnetic field. It will be understood of course, that this improvement is not limited in its application to furnaces employing the particular type of double-coil guidance illustrated in FIGS. 1 and 2, but may also be applied, for example, to furnaces in which the upper winding is omitted, as shown in application Serial No. 32,215, and to furnaces wherein the two coils are energized in bucking magnetic flux relation, as shown in application Serial No. 32,216, both further identified above.

In FIG. 2, the volume occupied by the conelike electron beam is represented by the shading between lines 40 and 41 and between lines 42 and 43. It will be noted that the beam is everywhere substantially parallel to the magnetic flux lines 19 that converge and extend through the center opening of winding 13 into the open top end of mold 1.

In FIG. 1, there is schematically shown a vacuum tank 44 which encloses the casting mold 1, the electron gun, and associated parts. Tank 44 is continuously evacuated to a high vacuum, preferably one micron of mercury absolute pressure or less, by connection through a large-area duct 45 to high-capacity vacuum pumps 46. Appropriate air locks (not shown) may be provided as desired for the introduction of melt stock, the removal of ingots, the replacement of electron guns, and the like.

FIG. 3 shows a modification wherein the flux concentrator serves the additional purpose of altering the shape of the magnetic field so that the converging flux lines that guide the electron beam extend downwardly and inwardly toward the open top end of the casting mold at smaller angles to the horizontal. This is especially advantageous when the melt stock is to be introduced as a vertical rod extending downward in coaxial alignment with the casting mold. The casting mold 1, cast ingot 3, and winding 6 may be identical to the corresponding parts shown in FIG. 2. An annular electron gun comprises cathode 47, accelerating electrode 48, and focusing electrode 49. The electron gun may be similar to the annular gun shown in FIG. 2, except that in FIG. 3 the gun is spaced much closer to the casting mold relative to the diameter of the gun, which may be somewhat larger in this embodiment.

The flux concentrator comprises two horizontal rings 50 and 51 of ferromagnetic material connected together by a ferromagnetic yoke 52, which, it will be noted, passes outside of winding 6. Ring 50 extends coaxially around mold 1 below winding 6 whereas ring 51 is disposed immediately above and outside of the annular electron gun (spaced therefrom just enough for electrical insulation) so as to concentrate the magnetic flux along paths passing through the gun. Typical flux paths are represented by broken lines 53, and the electron beam occupies the volume represented by the shaded area between lines 54 and 55 and between lines 56 and 57. It will be noted that the electron paths extend downwardly and inwardly at an angle of about 45° to the horizontal.

The melt stock is a vertical rod 58 fed downwardly through the annular gun into the hollow conelike electron beam, in vertical coaxial alignment above the open top of mold 1. As the lower end of rod 58 advances into the beam, it is melted away and the so-melted material drops into the open top end of mold 1 for maintaining a pool 3' of molten material atop the newly cast ingot 3. Feed mechanism for the melt stock is symbolized by the rollers 59 driven by electric motor 60. The melt stock is electrically connected to ground, e.g., through the rollers 59 which may be grounded, as indicated by the symbol 61. The casting mold, electron gun, and associated parts are included within a continuously evacuated tank, as in the embodiment shown in FIG. 1.

It will be understood that the specific embodiments illustrated are but two examples of how this invention may be carried out, and that further changes and modifications are possible without departing from the inventive principles herein disclosed.

What is claimed is:

1. An electron-beam furnace comprising a container for molten material, said container having an open top, means providing a magnetic field having flux lines converging into said container through its open top, an electron gun aligned to project a beam of electrons along said converging flux lines into said container, a first flux concentrator of ferromagnetic material adjacent to said gun, a second flux concentrator of ferromagnetic material adjacent the container, a yoke of ferromagnetic material connecting the first and second flux concentrators for increasing the magnetic field strength in the vicinity of the gun and between the two concentrators, a vacuum tank enclosing at least the space between said gun and said container, and means for evacuating said tank continuously.

2. An electron-beam furnace as in claim 1, said means supplying a magnetic field comprising an electromagnet winding extending around said container and having a vertical axis substantially concentric with said open top, said first flux concentrator comprising a ring of ferromagnetic material in vertical, coaxial alignment with said winding, said electron gun being annular and lying between said ring and said winding.

3. An electron-beam furnace comprising an annular container for molten material, said container having a vertical axis and an open top end, a first ring of ferromagnetic material extending around said container, a second ring of ferromagnetic material vertically spaced above the open top end of said container, a yoke of ferromagnetic material connecting said rings, means providing between said rings a magnetic field having flux lines extending through the open top of said container, an electron gun disposed and aligned to project a beam of electrons along said flux lines into said container, a vacuum tank enclosing at least the space between said gun and said container, and means for evacuating said tank continuously.

4. An electron-beam furnace comprising an annular metal mold having a vertical axis and having an open top end for receiving melted material, an annular electromagnet winding extending coaxially around said mold below said open top end, a first horizontal ring of ferromagnetic material extending coaxially around said mold below said winding, an annular electron gun vertically spaced above the open top end of said mold in vertical coaxial alignment with the mold and said winding, a second horizontal ring of ferromagnetic material closely spaced above said gun in vertical coaxial alignment therewith, a yoke of ferromagnetic material connecting said first and second rings and extending outside of said winding, direct-current supply means connected to energize said winding, the so-energized winding providing between

said rings a magnetic field having flux lines extending and converging downwardly through the open top end of said mold, said electron gun being shaped and aligned to direct a hollow, conelike beam of electrons downward and inward along said converging flux lines, means for progressively feeding material to be melted into the electron beam above the open top end of said mold, a vacuum tank enclosing said electron gun and said mold and the space therebetween, and means for continuously evacuating said tank.

5. An electron-beam furnace as in claim 4, additionally comprising a second electromagnet winding vertically spaced above the open top end of said mold and below said electron gun, the two windings being in vertical coaxial alignment, and means energizing said second winding in additive magnetic flux relation to the first winding.

6. An electron-beam furnace as in claim 4, the inside diameter of said second ring being larger than the vertical spacing between said second ring and the top end of said mold, the melt stock being fed vertically downward through the center of said second ring and said annular electron gun.
